(57) **CLAIM**

The ornamental design for a portable fan with bendable monopod and guard cover set, as shown and described.

DESCRIPTION

FIG. 1 is a perspective view of the portable fan with bendable monopod and guard cover set of our new design in a first configuration, with a bent monopod and without a guard cover;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is a front view of the portable fan with bendable monopod and guard cover set in a second configuration, with the monopod in a straight position and with a guard cover;

FIG. 9 is a rear view thereof;

FIG. 10 is a right side view thereof, with the left side view being a mirror image thereof;

FIG. 11 is a top view thereof; and,

FIG. 12 is a bottom view thereof.

The broken lines showing of a rod in FIG. 1 is for the purpose of illustrating environmental structure and forms no part of the claimed design.

The broken lines in FIG. 2 and FIG. 8 illustrate portions of the portable fan with bendable monopod and guard cover set that form no part of the claimed design.
